FURNITURE FASTENING DEVICE

Guy T. Hobbs, Dover, Pa.

Application November 10, 1953, Serial No. 391,261

5 Claims. (Cl. 311—110)

This invention relates to a furniture fastening device and more particularly to a fastening device for furniture of the knockdown type.

The advantages of knockdown furniture are well known. Great savings in shipping costs are effected, and, because of the lower labor costs involved, the furniture may be marketed at a competitive advantage. One disadvantage, however, in known knockdown furniture is that the fastening elements utilized are such that the articles are difficult to assemble in the absence of considerable skill, and that, once assembled, the constituent elements have a tendency to become loose, even under the stresses incident to normal use.

With the foregoing in mind, a principal object of the invention is to provide a furniture fastening device for furniture of the knockdown type capable of securing furniture components in rigid relation in the absence of the necessity for considerable skill on the part of the assembler, and with a tool of no more complexity than a simple household hammer.

A further object of the invention is to provide a furniture fastener of the stated type wherein furniture components can be readily assembled and can just as easily be disassembled, should that be desired.

A further object of the invention is to provide a fastening device of the character described wherein assembly and disassembly can be effected without damage to the constituent elements of the furniture.

The invention resides further in certain structural details hereinafter described and illustrated in the attached drawings wherein:

Fig. 1 is a top plan view of a fastening device made in accordance with the present invention;

Fig. 2 is a vertical elevational view, on an enlarged scale of the fastener of Fig. 1;

Fig. 3 is a side elevational view, partly in section, of 50 the fastener shown in Fig. 2;

Fig. 4 is an enlarged fragmentary view in perspective of one element of the fastening device; and

Fig. 5 is an enlarged view in perspective of the other element of the fastening device.

With reference to the drawing and more particularly to Figs. 4 and 5, it will be seen that a fastening device is provided comprising two separate elements, generally indicated by reference numerals 10 and 11, the latter of which including the furniture leg as an integral part 60 thereof.

In accordance with my invention, the element 10 consists of a substantially flat clip, the body 12 of which is secured to the underside of a flat furniture member such as a table top or the like by means of fastening elements 13 inserted through apertures 14, and the tab portion 15 of which engages an edge portion of the furniture member. Tabs 16, integral with the body portion 12 and coplanar therewith before assembly, are provided for a purpose hereinafter described. A tapered socket for the reception of the tongue 17 of the element 11 is formed by inturning the edges 18 of the clip 10. It will be understood that this clip is normally secured to the furniture member during transit.

2

To assemble the furniture piece the tongue 17 is inserted in the tapered socket of the clip so that the flat wing portions 19 of the member 11 snugly engage the edge of the furniture member. Fastening elements 22 are 5 then inserted in the apertures 23 and into the furniture member and the tabs 16 are struck down into the recesses 24 of the element 11, as shown best in Figs. 2 and 3. The corners 25 of the tongue, which protrude beyond the recess 26 in the rear edge of the clip, are then 10 bent upwardly over the bevelled edges 27 of the recess as best shown in Figs. 1 and 3.

Should additional rigidity be desired, one of the fastening elements 13 can be removed before insertion of the tongue in the socket and inserted through an aperture 28 in the tongue registering with an aperture 14 of the clip. Although the element 11, in this instance, is shown as a furniture leg per se, the bottom of this element being elongated as required, I contemplate the use of such an element as a structural support member for a leg of wood or like material, or as one of two complementary fastening elements for securing a wide variety of furniture components.

I claim:

1. A fastening device for furniture of the knockdown type, said device comprising a clip having a flat body portion with turned opposite edges forming therebetween a tapered open ended socket and means for securing said body portion against a flat surface of a furniture piece at an edge of the latter and with the relatively wide open end of the socket confronting said edge, a locking tab projecting from the edge of the body portion in the plane of the latter and beyond the said open end of the socket so as to project also beyond the said edge of the furniture piece at which the clip is secured, and a complementary member having a tapered tongue fitting and adapted for insertion in said socket together with a body portion extending from said tongue at an angle to the plane of the latter, said tab when the tongue is fully inserted in the socket extending beyond the outer edge 40 of the latter and being adapted for angular displacement from its normal plane over and against said outer edge to thereby lock the tongue in the socket.

2. A fastening device according to claim 1 wherein the tongue when fully inserted in the socket projects at its inner end beyond the proximate edge of the body portion of the clip, and is provided at said inner end with an angularly displaceable portion arranged when so displaced to interlock with the said edge of the clip to further immobilize the complementary fastening member in the clip socket.

3. A fastening device according to claim 1 wherein said complementary member is provided with wing portions, one on each side of said tongue and perpendicular thereto, and adapted to engage the said edge of the furniture piece.

4. A fastening device according to claim 1 wherein said clip is provided at one edge thereof with a tab portion extending perpendicular to said body portion.

5. A fastening device according to claim 1 wherein said tab is received in a recess in said complementary member.
